(57) **CLAIM**

The ornamental design for an adjustable-incline climbing wall, as shown and described.

DESCRIPTION

FIG. 1 is a top and front, right side perspective view of an adjustable-incline climbing wall showing our new design; FIG. 2 is a top and rear, right side perspective view thereof; FIG. 3 is a front elevation view thereof; FIG. 4 is a rear elevation view thereof; FIG. 5 is a right side elevation view thereof; FIG. 6 is a left side elevation view thereof; FIG. 7 is a top plan view thereof; and, FIG. 8 is a bottom plan view thereof.

The broken lines in the drawings illustrate portions of the adjustable-incline climbing wall that form no part of the claimed design.

1 Claim, 6 Drawing Sheets
